(57) **CLAIM**

The ornamental design for a sunglasses holder for car visor, as shown and described.

DESCRIPTION

FIG. 1 is a perspective view of a sunglasses holder for car visor design showing my new design.

FIG. 2 is another perspective view thereof.

FIG. 3 is a front view thereof.

FIG. 4 is a rear view thereof.

FIG. 5 is a left side view thereof.

FIG. 6 is a right side view thereof.

FIG. 7 is a top view thereof.

FIG. 8 is a bottom view thereof.

FIG. 9 is its folded state view thereof; and,

FIG. 10 is its expanded state view thereof.

The broken lines in the drawings illustrate the portions of the sunglasses holder for car visor, which form no part of the claimed design.
